UNITED STATES PATENT OFFICE.

EDWARD W. HUTCHINSON, OF CHICAGO, ILLINOIS.

DESIGN FOR A TOOL-HANDLE.

SPECIFICATION forming part of Design No. 22,633, dated July 18, 1893.

Application filed June 12, 1893. Serial No. 477,377. Term of patent 14 years.

To all whom it may concern:

Be it known that I, EDWARD W. HUTCHINSON, a citizen of the United States, residing in Chicago, in the county of Cook and State 5 of Illinois, have invented and produced a new and original Design for Tool-Handles, of which the following is a specification, reference being made to accompanying drawing, forming a part thereof.

10 The drawing shows in perspective my newly designed tool handle.

The tool handle consists of a cylindrical portion *a*, having substantially straight parallel sides, and scored at *a'*, *a'*, a rounded end 15 portion *b*, a cylindrical portion *c* gradually decreasing in diameter from *a'*, to *c'*, and gradu-

ally increasing in diameter from *c'*, to *c*², and a rounded end portion *d*, with a flat face *d'*; thereby presenting as a prominent feature a circumferential enlargement at the tool receiving end, and next a contracted neck having curved sides.

I claim—

The design for a tool handle herein shown and described.

In testimony whereof I have signed my name to this specification in the presence of two subscribing witnesses.

EDWARD W. HUTCHINSON.

Witnesses:

B. J. NOYES.

EVA S. ROUNDS.
